DEVICE FOR CREEASING TROUSERS

R. B. Worden, Granger, Wash.

Application January 12, 1937, Serial No. 120,293
Renewed March 21, 1939

4 Claims. (Cl. 38—72)

This invention relates to improvements in devices for creasing trousers and pertains particularly to a device which may be made in a size which will facilitate its easy portability.

The primary object of the present invention is to provide a novel pants pressing or crease forming device which may be applied to the pants and left thereon while the same are laid aside so that when they are to be worn, they will be properly creased and stretched.

Another object of the invention is to provide a device of the above described character having a novel means for gripping and holding together the front and rear of both legs of the trousers whereby a single pressure applying unit may be used for forming the front creases of the two legs and a second single unit may be employed for forming the creases at the rear of the two legs.

The invention broadly contemplates the provision of an elongated leaved unit and a gripping unit associated therewith, by means of which two creases may be simultaneously formed. Each leaved unit and pressure applying unit takes care of the formation of two creases, there being one pair of these units at the front of the trousers and another pair at the rear of the trousers. In association with the two pairs of units are spreader devices by means of which the cloth of the trousers between the creases may be held tight while the creasers are in use.

A still further object of the invention is to provide a portable creasing device for trousers which is adapted to be folded with the trousers after having been applied thereto so that the trousers may be transported conveniently in a suitcase, trunk or similar device.

The invention will be best understood from a consideration of the following detailed description taken in connection with the accompanying drawing forming part of this specification, with the understanding, however, that the invention is not confined to any strict conformity with the showing of the drawing but may be changed or modified so long as such changes or modifications mark no material departure from the salient features of the invention as expressed in the appended claims.

In the drawing:

Figure 1 is a view in side elevation of the device partly assembled and shown applied to a pair of trousers.

Figure 2 is a sectional view on the line 2—2 of Figure 1.

Figure 3 is a view in perspective of one end of one side portion of the device.

Figure 4 is a section on the line 4—4 of Figure 1.

Figure 5 is a section on the line 5—5 of Figure 1.

Referring now more particularly to the drawing, wherein like numerals of reference designate corresponding parts throughout the several views, the numeral 1 designates a pair of trousers to which is shown applied the creasing device embodying the present invention. This creasing device consists of two parts which are duplicates one of the other, one part being used to crease at one time the two legs of the trousers at the front, while the other part is employed in the same manner at the back of the trousers. Each of these parts consists of a leaved unit, which is indicated generally by the numeral 2, and a gripping unit which is indicated generally by the numeral 3, and which is used in association with the leaved unit. Each leaved unit comprises a central leaf 4 and the two outer leaves 5, each of these three leaves being provided along one edge with the integrally formed hinge sleeves or knuckles 6, which are engaged to bring them into alinement to facilitate the extension therethrough of the rod 7 which serves as a hinge pin on which the leaves oscillate and is a means for retaining the leaves in interconnected relation.

The central leaf of each unit 2 is perfectly flat, while the outer leaves between which the central leaf is located, are transversely bowed, the convex sides thereof being in opposed relation with the intermediate or center leaf 4 so that when the free edges of the outer leaves are drawn together, the convex surfaces will exert considerable pressure against the sides of the center leaf and consequently against any body which is interposed between the outer leaves of the center leaf, such as the cloth material of the trouser leg.

The rod 7 at each end is formed into an eye 8, the purpose of which will be hereinafter described.

The gripping device 3 is in the form of an elongated channel of substantially U-shaped cross section, thus giving to it the spaced substantially parallel walls 9, which are connected by the integral intermediate yoke portion 10. The free edges of the sides 9 of the gripper are turned inwardly to form the flanges 11 and the gripper unit 3 is of sufficient depth to slide over the leaved unit 2 so as to completely house the lat-

ter and engage the free edges of the outer leaves 5 in the grooves 11.

The units 2 and 3 may be formed of sufficient length to extend the full length of the crease 5 which is to be formed in each trouser leg or they may be made in shorter sections and arranged in end to end relation when in use. While the illustration of the invention shows two complete devices at the front of the trousers 1 and 2 and at the rear, it is to be understood that the invention is not confined to the formation of the devices in short portions or in pairs, as illustrated, but that there may be a single complete device at the front and a complete one at the rear, if 10 desired.

At one end of the leaved unit 2 which may be nearest the bottom of the trousers when two units are used in alinement in the manner shown, or at the end of the unit which engages the cuffs 20 of the trousers when a single device is used, the outer leaves are transversely divided to form the short independent portions 5a. These portions engage over the cuffs of the trousers. This takes care of the increased thickness of the material at this end of the garment so that when the gripping unit 3 is placed in position, the longer portions of the outer leaves may be forced in further than those portions between which the trouser cuffs are placed.

30 In applying the devices to the trousers, the material of each trouser leg is placed between a central leaf and a side or outer leaf so that one unit 2 engages or grips two legs of the trousers. The gripper 3 is then slid longitudinally over the unit 2 and being of substantially rigid material and having the free edges thereof arranged in relatively close relation, the free edges of the leaves 5 will be forced together and thus tightly compress the material of the legs of the trousers 40 between the outer leaves and the central leaf along the area adjacent to the hinge connection between the leaves.

After the two complete devices have been applied to the front and rear of the trousers, a centrally looped spreader spring 12 is engaged between the adjacent eyes 8 at the bottom of the garment, as illustrated. This spreader spring may be provided with hooks at each end, as indicated at 13, for engagement in the eyes and is so designed that it must be placed under tension in order to engage the hooks in the eyes, thus when the spring is released, its normal tendency to straighten out will create a stretching action upon the material of the trouser legs between the front and rear creasing devices. An eye 14 is formed at the center of the spreader spring to facilitate hanging up the garment.

At the opposite end of the garment, a similar spreader spring 15 is connected between the adjacent eyes 8 of the devices, this spring being provided also with hooks at its ends, as indicated at 16, to engage in the eyes. However, this spring need not have the hanger loop, such as is indicated by the numeral 14 in the spring 12 but may be made of a substantially straight piece of material.

When two or more short devices are used in longitudinal alinement at the front and rear of the trousers, in the manner illustrated, then the adjacent eyes 8 of the alined devices may be arranged in overlapping relation and a central spreader spring 15a, of the same construction as the spring 15, can be connected between the center eyes of the front and rear pairs of the devices. This central spring forms the double

function of coupling the adjacent ends of the devices together and exerting a spreading or stretching action upon the material of the garment intermediate its ends.

From the foregoing it will be readily apparent that with a device of the character herein described, a pair of trousers may receive a continuous pressing application while being stored away so that when they are to be used they will be found completely and properly creased. It will also be apparent that the device herein described is of simple construction and may be economically produced and also that by forming the front and rear portions in short lengths instead of in lengths equaling the lengths of the trouser legs, 15 the trousers may be folded to be placed in a suitcase or trunk.

I claim:

1. A crease forming device for trousers, comprising an elongated unit having three leaves pivotally coupled together to be relatively moved for separation on an axis extending longitudinally thereof for the insertion of portions of the legs of the trousers, the outer ones of said leaves being resilient and transversely bowed with the convex 25 faces opposing the center leaf, and an elongated longitudinally channeled inflexible casing formed to have said unit inserted thereinto from one end thereof and so constructed and arranged as to contact the outer leaves along the longitudinal 30 edges thereof remote from the pivotal coupling therebetween and force the outer leaves inwardly against the center leaf, the casing being of a width less than the distance between the said edges of the leaves before the casing is applied. 35

2. A crease forming device for trousers, comprising an elongated unit having three leaves pivotally coupled together along longitudinal edges to be separated for the insertion of portions of the legs of the trousers, the outer ones of said leaves being resiliently and transversely bowed with the convex faces opposing the center leaf, an inflexible compressing member of substantially U-shaped cross sectional design adapted to receive said unit with the free edges of the leaves 40 disposed adjacent the outer edges of the member and inwardly directed grooves along the said outer edges of said member in which the free longitudinal edges of the outer leaves are engaged, said member when engaging the unit forcing the outer leaves thereof together to compress the inserted trouser leg material between the outer leaves and the center leaf. 45

3. A cloth creaser of the character described comprising an elongated flat leaf of material, a 55 resilient transversely bowed leaf lying upon each side of the flat leaf, the three leaves being formed along one edge of the group to provide interconnected hinge knuckles, a pivot pin joining said knuckles, the bowed leaves having their convex 60 sides opposing the flat leaf, a member of U-shape having a width from the yoke of the U to the ends thereof slightly greater than the width of the leaves and receiving the leaves between its sides whereby the joined edges are adjacent said yoke 65 and the free edges of the outer leaves lie inwardly of the free ends of the U, and inwardly directed channels formed at the said ends of the U into which the free edges of the bowed leaves are engaged, the said joined leaves being inserted longitudinally and between the sides of the U member and the width of the U member being less than the distance between the free edges of the bowed leaves before the leaves are inserted whereby the said leaves are flexed inwardly by the U member. 70 75

4. A crease forming device for trousers, comprising an elongated plate, a pair of plates of corresponding width and length having the first plate therebetween, said pair of plates being resilient and transversely bowed with the convex faces opposing the first plate, pivotal means coupling the plates together along longitudinal edges thereof facilitating movement of the outer plates relative to the first plate on an axis extending

longitudinally of the plates, and an elongated longitudinally channeled compressing unit into which the plates are longitudinally inserted, said unit being so constructed and arranged as to effect the forcing together of the free longitudinal edges of the said pair of plates to compress trousers legs interposed between them and the first-mentioned plate. 5
